US00D402758S

United States Patent [19]

Barkley et al.

[11] Patent Number: Des. 402,758

[45] Date of Patent: **Dec. 15, 1998

[54] AUTOMATED EXTERNAL DEFIBRILLATOR

[75] Inventors: **Steven D. Barkley**, Champlin; **Robert K. Johnson**, Blaine; **Kenneth F. Olson**, Edina, all of Minn.

[73] Assignee: **SurVivaLink Corporation**, Minneapolis, Minn.

[**] Term: **14 Years**

[21] Appl. No.: **68,736**

[22] Filed: **Apr. 1, 1997**

[51] LOC (6) Cl. **24-01**

[52] U.S. Cl. **D24/167**; D24/168

[58] Field of Search **D24/167, 168, D24/165; 607/5, 8, 4, 6, 7**

CLAIM

The ornamental design for an automated external defibrillator, as shown and described.

DESCRIPTION

FIG. 1 is an isometric view of the automated external defibrillator according to the present invention;

FIG. 2 is a front view of the automated external defibrillator according to the present invention;

FIG. 3 is a right side elevational view of the automated external defibrillator;

FIG. 4 is a left side elevational view of the automated external defibrillator;

FIG. 5 is a back view of the automated external defibrillator;

FIG. 6 is a top plan view of the automated external defibrillator; and,

FIG. 7 is a bottom plan view of the automated external defibrillator.

1 Claim, 5 Drawing Sheets
